UNITED STATES PATENT OFFICE.

GEORGE F. VOIGHT, OF SAN FRANCISCO, CALIFORNIA.

HORN.

1,351,223.

Specification of Letters Patent. Patented Aug. 31, 1920.

Application filed March 21, 1919. Serial No. 284,028.

To all whom it may concern:

Be it known that I, GEORGE F. VOIGHT, a citizen of the United States, and resident of the city and county of San Francisco, State of California, have invented a new and Improved Horn, of which the following is a specification.

My invention relates to a type of horn adapted to be carried by a road vehicle or 10 the like, operable for giving phonetic warning signals, and in which a diaphragm is vibrated by mechanical means.

An object of my invention is to provide a horn having a supporting bracket adapted 15 to be rigidly secured to a portion of the vehicle, the bracket pivotally supporting the horn, and the horn movably engageable with a portion of the bracket for operating mechanism adapted to vibrate the diaphragm.

Another object of the invention is to provide a horn free from any opening in its 20 top or end walls of the casing through which project operating levers or the like. Such an opening, or openings, when the vehicle

25 to which the horn may be attached is being washed, or when the horn is exposed to rain, is liable to permit water or moisture to enter to the detriment of the working parts contained inside the casing.

A further object of the present invention 30 is to eliminate the usual operating arm projecting out from the casing, which is unattractive and liable to catch on the clothing of the operator.

Still another object is to provide a horn 35 in which the axis of its resonator, during the operation of the horn, will oscillate, thereby changing the direction in which the sound waves emitted by the horn will travel 40 and giving a distinctive effect to the tone of the warning.

With the foregoing and other objects and 45 purposes in view which will appear as the description proceeds, the invention resides in the combination and arrangement of parts and in the details of construction herein-after described and claimed, it being understood that changes in the precise embodiment of the invention herein disclosed can be 50 made within the scope of what is claimed without departing from the spirit of the invention.

The invention is illustrated, more or less

diagrammatically, in the accompanying drawings, wherein—

Figure 1 is a longitudinal elevation of the horn; Fig. 2 is a longitudinal sectional view; Fig. 3 is a view partly in section, of the horn moved downwardly from its normal position; Fig. 4 is a sectional view on line 60 *b*—*b* in Fig. 1; Fig. 5 is a sectional view on line *a*—*a* in Fig. 1 and Fig. 6 is a detailed view in perspective of a portion of the supporting bracket.

Like numerals of reference designate like 65 parts throughout the several views.

Referring now to the drawings in detail, 1 designates a bracket plate rigidly secured to a base 2 by means of screws 3. The base 2 may form a portion of the frame of a 70 vehicle.

One end of the bracket 1 is struck upwardly, thereby forming a relatively short arm 4 having its upper or free end bifurcated and formed into a pair of spaced apart 75 ears 5 provided with openings 6, which support the outer ends of a pivot pin 7.

8 designates the resonator, 9 the diaphragm and 10 the walls of the mechanism chamber, of a horn constructed and assembled in a manner common to the type of 80 horn to which my horn in general belongs.

To the lower side of the resonator 8 is rigidly secured a plate 11, by means of a rivet 12. The plate is provided at one end 85 with an opening 13 through which rotatably extends the pivot pin 7. The arrangement being such that the resonator 8 may be oscillatorily supported by the pivot pin 7.

The opposite end of the bracket 1 is also 90 struck upwardly thereby forming a relatively long arcuated arm 14, the upper end portion of which extends into the horn through an opening 15 in the wall 10 and is provided with a slot 16, thereby forming 95 two oppositely disposed members 17 and 18. (See Figs. 5 and 6. In Fig. 6 the members are shown before being curved or arcuated.) The upper portion of the member 17 is provided upon its concaved side 100 with teeth 19, which engage teeth 20 of a pinion gear 21, which is disposed centrally upon one side of a rotor 22 and is integral therewith.

The rotor and pinion are rigidly secured 105 to a shaft 23, which has its outer ends jour-

naled in bushings 24 disposed in openings 25 in the walls 10. The shaft is provided with pins 26 for restricting longitudinal movement thereof relatively to the bushings.

Upon the periphery of the rotor 22 are teeth 27 engageable with an anvil 28 centrally disposed upon the diaphragm 9.

29 designates a projection on the upper 10 end of the member 17, to which is secured the upper end of a contractile coil spring 30. The lower end of the spring is secured to a lip 31 struck inwardly from the wall 10 adjacent the opening 15.

32 is a button or boss rigidly secured to 15 the wall 10, and adapted to be engaged by the hand of the person operating the horn.

To operate the horn, presuming for illustration that the horn is in its normal position, which is the position of the horn as depicted in Figs. 1 and 2, the operator strikes or presses downwardly upon the button 32 thereby causing the horn to oscillate upon the pivot pin 7 and the rear end thereof to 25 move downwardly along an arcuated line of which the pivot pin 7 is the radial point, into approximately the position shown in Fig. 3, the teeth 20 of the pinion gear 21 being in engagement with the teeth 19, the 30 said downwardly movement of the rear end of the horn will cause the rotor 22 to rotate and the teeth 27 to impinge the anvil 28 and vibrate the diaphragm. The downwardly movement of the horn will cause the spring 35 30 to extend longitudinally against its tension, and it is intended that the spring be made strong enough so that the tension thereof will cause the horn to oscillate back to its initial or normal position after the 40 down stroke of the horn has been completed.

In order to facilitate the description of the horn and in defining its operation and functions, in this specification, the resonator end of the horn is designated the "front 45 end" and that portion thereof on the opposite side of the diaphragm from the resonator is designated the "rear end."

I claim:

1. The combination with the body portion 50 of an oscillatory horn, embodying a resonator, a diaphragm and casing rigidly secured together, and means movable relative thereto disposed inside the casing for operatively engaging and vibrating said diaphragm, of 55 an opening in the lower side of said casing, a bracket having one end disposed below said resonator and pivotally connected thereto and another end disposed below said casing and having a projection extending 60 through said opening and operatively in engagement with said means, and a spring engaging said bracket and horn adapted to yieldingly support the horn against oscillation.

65 2. The combination with the body por-

tion of an oscillatory horn embodying a resonator, a diaphragm and casing, means for rigidly securing said resonator diaphragm and casing together, and movable mechanism disposed inside said casing 70

adapted when moved to vibrate said diaphragm, said mechanism including a toothed member, of a pivot pin disposed outside of said casing, a connection between said pin and the horn, an opening in the lower side 75 of the casing, a bracket adapted to be rigidly secured to a base, a connection between one end of the bracket and said pivot pin, the other end of said bracket extending through said opening and provided with 80 teeth on its free end adapted to operatively engage said toothed member.

3. The combination with an oscillatory horn of the character described, including a diaphragm, a casing rigidly secured to one 85 side of said diaphragm, a resonator rigidly secured to the opposite side thereof, and means disposed inside the casing and movably engageable with the diaphragm for vibrating it, of a bracket adapted to be supported by a base and disposed so as to have a portion projecting forwardly of said diaphragm and another portion projecting rearwardly thereof, a pivotal connection between said forwardly projecting portion 90 and the horn, a connection between said rearwardly projecting portion and said means whereby said means may be operatively moved for engaging and vibrating the diaphragm when the horn is oscillated in one direction upon the bracket, and resilient means for oscillating the horn in the opposite direction.

4. The combination with an oscillatory horn of the character described, including a 105 diaphragm, a casing rigidly secured to one side of said diaphragm, a resonator rigidly secured to the opposite side thereof, and means rotatably mounted in the casing and movable relative to the diaphragm for 110 operatively engaging and vibrating it, of a bracket adapted to be rigidly supported by a base, a pivotal connection between one section of the bracket and the horn for oscillatorily supporting one end thereof, and a 115 connection between another section of the bracket and said means whereby said means may be operatively moved for engaging and vibrating the diaphragm when the horn is oscillated in one direction, and resilient 120 means for oscillating the horn in the opposite direction.

5. An oscillatory horn of the character described, comprising a vibratory diaphragm, a casing rigidly secured to one side of said 125 diaphragm, a resonator rigidly secured to the other side thereof, means carried by the horn and movable relatively to the diaphragm for operatively engaging and vibrating it, a bracket adapted to have a sec- 130

tion supported by a support, a connection between a portion of said bracket and the horn for oscillatorily supporting it, a connection between another portion of the bracket and said means whereby said means may be operatively moved for engaging and vibrating the diaphragm when the horn is oscillated in one direction, and resilient means for oscillating the horn in the opposite direction.

6. The combination with an oscillatory horn of the character described, embodying a vibratile diaphragm, a casing rigidly secured to the diaphragm at one side thereof, a resonator rigidly secured to the diaphragm at the opposite side thereof, and means rotat-

ably mounted in the casing and movable relative to the diaphragm for operatively engaging and vibrating it, of a bracket disposed exteriorly of the horn adapted to have a portion rigidly secured to a support, a connection between a portion of the bracket and the horn for oscillatorily supporting the horn, a movable connection between another portion of the bracket and said means whereby said means may be moved for operatively engaging and vibrating the diaphragm when the horn is oscillated in one direction, and a spring for oscillating the horn in the opposite direction.

GEORGE F. VOIGHT.
